UNITED STATES PATENT OFFICE.

THEODOR SCHIRRMACHER, OF BRADFORD, PENNSYLVANIA.

OIL-CAN.

SPECIFICATION forming part of Letters Patent No. 508,767, dated November 14, 1893.

Application filed February 27, 1893. Serial No. 463,860. (No model.)

To all whom it may concern:

Be it known that I, THEODOR SCHIRRMACHER, of Bradford, in the county of McKean and State of Pennsylvania, have invented certain new and useful Improvements in Oil-Cans; and I do hereby declare the following to be a full, clear, and exact description of the invention, such as will enable others skilled in the art to which it pertains to make and use it, reference being had to the accompanying drawings, which form part of this specification.

My invention relates to an improvement in oil cans; and it is particularly directed to the class employed in filling lamps in which the flow of oil from the spout thereof is automatically stopped by submerging the end of the inlet air passage in the oil within the lamp, and the novel features of my invention will be fully set forth hereinafter and especially referred to in the claims.

Referring to the accompanying drawings,— Figure 1 is a sectional view of a can provided with my improved spout, the former being shown tilted in the position when filling a lamp. Fig. 2 is a detached view of the spout.

A designates the can body of the ordinary or any preferred construction having a fixed top B, in which is a filling hole C, provided with the annular screw threaded flange D.

E is the improved filling tube having formed between its ends the circular flange F, and immediately above the said shoulder is the screw threaded enlargement F', of less diameter than the shoulder. The cap m, fitting the flange D, is provided with a central opening through which the said screw threaded enlargement projects and upon which latter the ring-nut G, is run, thereby clamping the cap m, between the shoulder F, and the ring G. Thus it will be seen that the tube may be easily applied to or removed from the can, and as I prefer to provide the can top with only one opening the same will have to be used both for filling the can and accommodating the filling tube so that the convenient removal of the same will be readily appreciated.

The tube E, is provided with a longitudinal partition H, which extends to nearly the rear

end of the same so that the said tube is divided into two separate passages which are connected at their inner ends. The extreme inner end of the tube E, is closed. The under passage I, constitutes the oil discharge while the upper passage J, the air inlet. Openings K, and L, are formed in the wall of the passage I, the opening K, being nearest the flange F.

In operation the can is tilted into the position shown in Fig. 1 when the oil from the can will flow through the opening K, and out through passage I, into the lamp while air will flow into the can from the lamp through the passage J, the current turning at the rear end of the same backward into the passage I, from which it discharges through the opening L, into the can. The flow of oil from the can continues until the end of tube E, within the lamp has been submerged. The flow of air into the can is then stopped and in consequence thereof the oil ceases to discharge from the same. A slight vacuum is formed in the can owing to the sudden stoppage of the air supply causing the oil to be drawn backward into passage J while upon the automatic stoppage of the oil flow from the passage I, the same is left full of oil. Both tubes are thus stopped with the fluid when the can is returned to its vertical position, and will remain so stopped until the can is again put into the filling position, as the vacuum in the can will prevent the oil from flowing thereinto from the two passages. The can is thus sealed while not in use in a most effectual manner.

The filler is automatic in its operation and by its use it is quite impossible to overrun a lamp.

Having thus fully described my invention, what I claim as new, and desire to secure by Letters Patent, is—

1. The combination of a can, a spout extending thereinto composed of two passages closed at their inner ends, the partition separating the passages terminating a short distance from their ends, thus placing the tubes in communication at this point, and openings K, L, in the lower tube, substantially as shown and described.

2. The combination of a can having formed in its top an opening, an annular screw threaded flange surrounding the same, a cap adapted to fit over the opening, a filling tube extending through the cap, a flange on the tube beneath the cap, a screw threaded enlargement extending through and above the cap, and a nut adapted to be run thereon, thus clamping

the tube to the cap, substantially as shown and described.

In testimony whereof I affix my signature in presence of two witnesses.

THEODOR SCHIRRMACHER.
